AUDIBLE WARNING SIGNAL

Theodore J. Scofield, Jackson, Mich., assignor
to The Sparks-Withington Company, Jackson,
Mich., a corporation of Ohio

Application June 18, 1937, Serial No. 148,981

7 Claims. (Cl. 177—7)

This invention relates to an audible warning signal for vehicles, for instance automobiles, and pertains more particularly to a warning signal in which a vibratory diaphragm is actuated by an electric motor of the magnetic type.

Signaling horns of this type are frequently, in present day practice, used in pairs, tuned to different frequencies. These horns are operated simultaneously, and the current for the motors being relatively heavy, is controlled by a relay which in turn is controlled by a manually operated switch of the push button type. In my co-pending application Serial Number 123,887, filed February 3, 1937, I have shown a pair of electrically operated horns of the magnetic type wherein a relay of such size and design as to satisfactorily control the heavy current necessary to operate both horns is mounted on a diaphragm case member of one of the horns of the group, and within the cover or cap therefor. Prior to the invention of my said application, the relay for such dual horns has always been mounted exteriorly of the horns, usually on a common bracket support for the horns.

The main object of the present invention is to provide a mounting structure for warning signals of the above mentioned type which is an improvement upon the structure shown in said co-pending application Serial No. 123,887.

In carrying out the above mentioned object, I have, by a change in the structure and arrangement of the parts of the contact stack for the motor, adapted the same to support also the relay for closing the circuit to the motor in such a manner that there is obtained an appreciable saving in materials and labor in the construction and assembly thereof.

The above and other objects and advantages pertaining to the structure of the contact stack and the arrangement of the parts thereof, and the manner of connecting the relay therewith, will more fully appear from the following description, taken in conjunction with the accompanying drawing, in which:

Figure 1 is a perspective view showing a complete dual horn assembly embodying the various features of this invention with a portion of one of the projectors broken away.

Figure 2 is a top plan view of a portion of Figure 1 with the horn caps removed.

Figure 3 is an enlarged detail transverse sectional view taken on line 3—3, Figure 2.

Figure 4 is a detail vertical sectional view taken on line 4—4, Figure 2, illustrating a portion of the cap mounted upon the diaphragm case sections.

Figure 5 is a perspective view of the upper positioned or rigid contact arm, and the relay armature operatively mounted thereon.

Figure 6 is a perspective view of a terminal

support usually mounted in the contact stack, and which is extended at one side to form a supporting bracket for the relay, together with a separate terminal member or plate associated therewith.

Figure 7 is a diagrammatic view of the wiring and arrangement of the horns and the relay.

The warning signal as illustrated in the drawing, comprises a pair of horns 1 and 2, which are mounted upon a common bracket 3 adapted to be attached by bolts or their equivalent, to a convenient portion of the motor vehicle for supporting the horns. These horns are constructed similarly except for the contact stacks; the contact stack for one of the horns, as 1, having the relay associated therewith, being of special construction, whereas the contact stack of the other horn, as 2, may be of any suitable well known construction. Each of these horns comprises a metal rear diaphragm case 5 having a central portion displaced laterally to form an integral substantially cylindrical cup-shaped member 6, said member being provided with a central opening 7 for the reception of an electro-magnet, presently described. A diaphragm 8 is clamped between the rear diaphragm case 5 and a front diaphragm case 9 by bolts 10 passing through aligned holes provided in the marginal portions of the diaphragm and diaphragm case section. The front diaphragm case section 9 is composed of metal and has the central portion thereof inclined outward, and arranged in opposed relation to the central portion 6 of the rear diaphragm case section for forming a diaphragm chamber 11 therebetween.

The central portion of the front case section 9 is provided with a centrally disposed forward extending annular flange 12, to which is secured in any suitable manner, a horn proper, or projector 13. The electro-magnet previously referred to may comprise a case member 14 adapted to extend from the inner side of the rear case section 5 outward through the opening 7, and is secured to the inner adjacent side of said case section in any suitable manner, as by legs 15, spot welded to said section. As indicated in Figure 4, the case 14 may be provided with a pair of transversely disposed slots 16 for the reception of a pre-formed field coil 17, which is constructed in any well known manner, and electrically insulated from the said case 14.

The diaphragm 8 is provided with a central opening in alignment with the opening 7 in the rear diaphragm case 5 for the reception of a bushing 20, which is provided with internal threads for the reception of the lower threaded end of a spacing sleeve 21. This sleeve 21 extends rearward from the diaphragm 8 and bushing 20 through a central opening 22 provided in the case 14, and has the upper end thereof arranged

in engagement with the armature 23 positioned adjacent the rear side of the case 14. The lower or forward end of the sleeve 21 projects a relatively short distance beyond the other face of the bushing 20, and has mounted thereon in any suitable manner a collar 24, which is slidably connected with the sleeve to form a fingerpiece by which the sleeve may be rotated to effect proper adjustment of the armature 23 with respect to the case 14.

Mounted within the sleeve 21 is a bolt or stud 25, which has the head 25' thereof arranged adjacent the collar 24 and spaced therefrom by washer 26. The other end of the bolt 25 extends rearward from the sleeve 21 through a central opening provided in the armature 23 to some distance at the rear of said armature. Mounted upon the bolt 25 is a bearing collar 27, which is seated in a suitable socket or recess provided in the outer or rear face of the armature 23, and which bears against a washer 28 mounted upon the stud or bolt 25 between the collar 27 and a nut 29, screw-threaded on the outer or rear end portion of the stud 25.

Clamped between the washer 28 and nut 29 is one end of a yielding support 30, which, in this instance is a flat spring member connected at the other end in any suitable manner, as by stud 31, to the rear diaphragm case section 5 at one side of the opening 7.

The structure thus far described is of conventional form and, as hereinbefore stated, may be alike in both horns 1 and 2. It will be understood that this conventional construction forms no part of my invention, and that other comparable constructions might be substituted therefor.

An automatic circuit breaker is provided for each horn, as is usual in motors of this type, to effect intermittent energizing and de-energizing of the magnet in synchronism with the movement of the diaphragm away from and toward the coil case 14. One of these circuit breakers is of special construction in that it is adapted to support a relay. This relay is so connected with the circuit breaker that upon actuation of a manually controlled switch or horn button, it will complete the circuit through the horn electro-magnets so as to avoid passing the heavy current required to operate the electro-magnets 50 through the manually controlled switch or horn button.

Not only is the contact stack of the circuit breaker of special construction for supporting the relay, but the relay itself must be of such a size and structure as to enable it to be mounted within the case or cover of a standard horn of the type under consideration, while at the same time making the relay positive in action and capable of operating successfully despite the vibration of the horn when said horn is being operated. That is, the electro-magnet of the relay should be strong so as to hold the armature closed against vibration. Also, the relay armature should be light, particularly at its free or contact end, and the armature spring should be relatively weak, both of which factors tend to reduce the possibility of accidental opening of the relay. In order to minimize the effect of the horn vibration, the relay and the specially constructed contact stack supportably associated therewith should be preferably combined with the horn, the pitch or frequency of which is further from the natural period of vibration of the relay. This will ordinarily be the horn of higher pitch.

The specially constructed contact stack con-

taining this invention and which is shown as mounted in the horn 1, comprises, as illustrated more particularly in Figures 3 and 4, a U-shaped supporting frame 32, which may be a sheet metal stamping, secured in inverted position to the central portion 6 of the rear case section 5 by electric welding or other suitable means adjacent one side of the opening 7.

To the upper transverse portion of the frame 32 is secured a pair of contact arms 33 and 34. These arms 33 and 34 are arranged in electrical insulated spaced relation to each other and to the frame 32 by insulating plates or spacers 35 and 36 and tubes 37. These tubes 37 surround a pair of screws 38 which extend downward through aligned holes provided in the contact arms and insulating plates into screw-threaded engagement with the frame 32 for securing said arms and plates to said frame. The arms 33 and 34 are positioned, as more particularly shown in Figure 4, adjacent the upper end of the contact stack in close proximity to each other and, in the structure shown, are not only insulated from each other by the plate 36, but are also electrically insulated from the frame 32 and screws 38 by the tubes 37 and plates 35, as illustrated more particularly in Figure 3. The arm 33 is provided with a contact point 33' which is adapted to engage a similar contact point 34' mounted on the arm 34. The contact arms 33 and 34 extend outward from the support 32 over the armature 23 and terminate in spaced relation to the stud 25.

The arm 33, in this instance is a rigid member, while the arm 34 is a flexible member in the form of a flat spring adapted to be actuated by the stud 25 through the medium of a nut 39 screw-threaded on the outer reduced end portion 25'' of said stud to move the contact point 34' out of electrical connection with the contact point 33'. The nut 39 is insulated from the contact arm 34 by the plate 36 which is extended over the outer or rear end of the arm. The nut 39 may be secured in the adjusted position upon the stud 25 by a lock nut 40.

Mounted in the contact stack beneath the contact arm 34 and in electrical contact therewith, is a terminal plate 42. The lower side of the terminal plate 42 is insulated by one of the insulating plates 35 which is mounted upon the screws 38 and tubes 37. Beneath the terminal plate 42 and the sub-adjacent insulating plate 35 is a second terminal plate 43 which is also electrically insulated from the contact arms 33 and 34, the terminal plate 42 and the bracket 32 by insulating plates 35 and tubes 37, as shown in Figure 3. One side of the terminal plate 43 extends downward in slightly spaced relation to the adjacent vertical leg of the bracket 32 and then outward to form a shelf 44 for supporting an electro-magnetic relay 45.

The relay 45 includes a coil 46 of insulated wire wound on a core 47 between insulating heads or spool ends 48 and 49 in the well known manner. The core 47 has its lower end 47' reduced in diameter and extended through a suitable aperture in the shelf 44, and may be peened or riveted over the adjacent surface of the shelf 44 for firmly securing the core and the relay coil 46 carried thereby to said shelf. The lower insulating head 49 is provided with an extension 50 carrying a screw terminal 51 to which is electrically connected one end of the coil 46. The other end of the coil 46 may be electrically connected to the core 47 and thence to the terminal plate 43.

A metal contact plate 52 is mounted between the enlarged upper end of the core 41 and the upper insulating head 48, and carries a contact point 52', which is adapted to cooperate with a similar contact point 53' mounted on the armature 53 of the relay 45. The armature 53 is a relatively light member and is supported by and electrically connected to the contact arm 33 by a flat metal spring 54.

As illustrated more clearly in Figures 5 and 6, the shelf 44 and the relay armature 53 are preferably offset from the contact stack toward the center of the horn mechanism, so as to permit enclosure of the relay within the conventional horn cap with ample clearance.

An electrical resistance 56 of any suitable construction is connected by suitable wires or electric conductors to the contact arm 33 and the terminal plate 42, and therefore across the contact points 33' and 34', for maintaining the field coil 17 partially energized during the periods the electric circuit is broken at the contact points 33' and 34'.

The electro-magnet, the circuit breaker and the relay just described may be enclosed by a cover 58 which is an inverted cup-shaped member having the marginal edge thereof surrounding the marginal edge of the rear case section 5 and engaging the marginal edge portion of the case section 9 which, as shown in Figure 4, is of slightly greater diameter than the rear case section for the purpose of supporting the cover. The cover 58 may be secured to the case section 5 in any suitable well known manner, as through the medium of a screw 59, which has threaded engagement with a suitable bracket (not shown) mounted upon the case section 5. A suitable grommet 60 is arranged in the cover 58 near the lower edge thereof in order to provide for the passage of the exterior wiring of the horn, as hereinafter described.

One end of the field coil 17 is connected by a wire or electrical conductor 61 to the terminal plate 42 and thence to the contact arm 34, and the other end may be grounded to the horn case, for example by connecting it under the head of one of the screws 38, as illustrated in Figures 2 and 3. Another wire 62 is connected at one end to the terminal plate 43, passes through the grommet 60, and serves to connect the horn to one side of a battery B, the other side of which may be grounded. A wire 63, likewise passing through the grommet 60, serves to connect the terminal 51 of the relay coil 46 to one side of a horn button or other switch S, the other side of which may also be grounded. A third wire 64 passing through the grommet 60 connects the contact arm 33 of horn 1 to the contact arm 33 of horn 2, thereby permitting the horns to be blown in unison. The foregoing wiring is shown diagrammatically in Figure 7. It will be understood by those skilled in this art that this is a so-called "one wire system," and that the often used "two wire system" could readily be substituted therefor.

The operation of this circuit will be evident from an examination of Figure 7. When the push button S is closed, a circuit is completed from the battery B through wire 62, terminal plate 43, shelf 44, core 41, relay coil 46, screw terminal 51, wire 63 and switch S to ground G, and thence back to the battery B. The current thus passing through the relay coil 46 actuates the armature 53 and closes a circuit from the battery B through

wire 62, terminal plate 43, shelf 44, core 41, contact plate 52, contacts 52' and 53', armature 53, spring 54, contact arm 33, contacts 33' and 34', contact arm 34, terminal plate 42, wire 61, field coil 17, and thence to ground and back to the battery. The consequent energization of the field coil 17 draws the armature 23 toward the case 14 and breaks the circuit just described at the contacts 33' and 34', but current still continues to flow therethrough, but to a lesser amount, through the resistance 56, in a manner and for a purpose well understood in this art. The resultant partial de-energization of the field coil 17 releases the armature 23, whereupon the circuit is re-established through the contacts 33' and 34', and the armature 23 is again drawn toward the case 14. The action just described is rapidly repeated so long as the horn button S is depressed, resulting in a corresponding actuation of the diaphragm 8 and the emission of an audible warning signal.

Simultaneously with the closing of the relay contact points 52' and 53', the current passing to the contact arm 33 of the horn 1 in which the relay 45 is mounted will pass to the contact plate 33 of the companion horn 2 through the medium of the wire 64. It will thus be seen that the motor contained in the horn 2 will be actuated simultaneously with the motor contained in the horn 1.

As soon as the switch or horn button S is released, the circuit passing through the relay coil 46 will be opened, thereby causing the armature 53 to be moved away from the core 41 by the action of the spring 54 and thereby open the circuit associated with the horn motors by the movement of the contact point 53' out of engagement with the point 52'. It will thus be seen that only a relatively light current will pass through the horn button S while the relatively heavy current required to operate the electro-magnets of the horns 1 and 2, is shunted around the switch S and passed directly to the horn motors.

Furthermore, it will be noted that by mounting the relay 45 inside of the cover 58 and upon the contact stack, not only are there no terminals exposed to the outside atmosphere, which eliminates to a marked extent the possibility of shortcircuiting of the mechanism or otherwise getting out of repair, but the entire assembly is more economical to manufacture. That is, the construction and arrangement of the parts described above enable an appreciable saving in the cost of a warning signal due to the elimination of a separate support for the relay and of a separate relay housing, wires, terminals, and so forth.

In addition, the adapting of the contact stack to support the relay by merely extending two previously employed members thereof, namely, the contact arm 33 and terminal plate 43, to support the armature and electro-magnet, respectively, of the relay 46, provides a unit which is less expensive and includes fewer parts than has heretofore been possible to obtain in the conventional structures.

It will be apparent that the relay construction hereinabove described is equally applicable to a single horn requiring heavy current or to three or more horns in lieu of the dual horn installation illustrated by way of example.

While I have described the preferred construction and arrangement of parts of the warning signal, I do not wish to be limited to the exact structure shown, as various changes and modifications may be made therein without de-

parting from the spirit of the invention as set forth in the appended claims.

I claim:

5. In a horn of the class having a diaphragm actuated by an electric motor of the magnetic type and a current supply circuit for said motor including a source of potential and a terminal mounted in the horn structure, a contact stack having a pair of coacting contact arms supported thereby in insulated spaced relation to each other, means connecting the contact arms in series in the electric motor circuit including a contact plate mounted in said contact stack in insulated spaced relation to said contact arms, said contact plate being extended to form a shelf at one side of the contact arms, a relay switch for closing a circuit through said contact arms having the core thereof secured to said contact plate shelf and electrically connected therewith, a coil on said core having one side electrically connected with the shelf and the other side electrically connected to said terminal, means resiliently and electrically connecting the relay armature with one of the contact arms, and a pair of coacting contacts connected respectively with said relay core and armature in electrical contact therewith adapted to be moved into and out of engagement with each other during the operation of the relay armature for closing the motor circuit.
10. In a warning signal of the class wherein a diaphragm carried by a frame is actuated by an electric motor of the vibratory type mounted on said frame and having an electric supply circuit therefor, in combination, a contact stack secured to the frame and including a pair of coacting contact arms connected in series in the motor current supply circuit, a relay having switch means mounted in the contact stack and connected in said motor circuit in series with said contact arms and adapted to be actuated upon the coil of the relay being energized for closing said motor circuit, and a coil supporting member for said relay clamped in said contact stack.
15. In a warning signal having a diaphragm carried by a frame and actuated by an electric motor of the vibratory type mounted on said frame and having an electric supply circuit therefor, in combination, a pair of coacting contact arms clamped in a contact stack secured to the frame in position to be actuated by the movement of the motor, said contact arms being connected in series in the motor current supply circuit, a relay comprising an energizing coil, an armature and a pair of contacts, said contacts being secured in the contact stack and connected in said motor circuit in series with said contact arms, and a coil supporting member for said relay clamped in said contact stack and forming a common terminal for one end of said relay coil and for one of said relay contacts.
20. In a warning signal having a diaphragm carried by a frame and actuated by the movement of an electric motor of the vibratory type mounted on said frame and having an electric supply circuit therefor, in combination, a pair of coacting contact arms clamped in a contact stack secured to the frame to be actuated by the movement of the electric motor, said contact arms being connected in series in the motor current supply circuit, a relay comprising an energizing coil, an armature and a pair of contacts, said contacts being secured in the contact stack and connected in series in said motor circuit, and a coil supporting member for said relay clamped in said contact stack and forming a common terminal for one end of said relay coil and for one of said relay contacts, one of said contact arms being electrically connected to said relay armature.
25. In a warning signal of the class having a diaphragm actuated by an electric motor of the magnetic type, a supporting frame for said diaphragm and motor, a circuit for said motor including a source of potential, in combination, a pair of coacting contact arms having a common support mounted on the frame, said arms being connected in series in said motor circuit, one of said arms being operatively connected to the diaphragm to effect intermittent energizing and de-energizing of the motor in synchronism with the movement of said diaphragm, a relay connected in said circuit having the coil thereof supported by said common support and the armature thereof resiliently supported by one of the contact arms and electrically connected therewith, and switch means associated with the relay armature so constructed and arranged that current will be supplied to said motor circuit upon operation of the relay.
30. In a warning signal having a diaphragm carried by a frame and actuated by the movement of an electric motor of the vibratory type mounted on said frame and having an electric supply circuit therefor, in combination, a contact stack including a frame member, a pair of contact arms mounted on said frame in insulated spaced relation thereto and to each other, a contact plate mounted on said frame in insulated spaced relation thereto and to said contact arms, means for electrically connecting one of the contact arms with the electric motor, means providing a circuit from the contact plate to the second contact arm including a relay having the core thereof supportably secured to the contact plate in electrical contact therewith and the armature thereof resiliently supported by and electrically connected with said second contact arm, a pair of coacting contact elements connected respectively with said relay core and armature in electrical contact therewith and engageable with each other when the armature is actuated upon said core being magnetized, and means for magnetizing said core.
35. In a contact stack for an electric motor of the magnetic type, a supporting frame, an electric circuit for said motor including a source of potential, a contact plate adapted to be connected with one side of said source of potential and mounted on said frame in insulated spaced relation thereto, a pair of contact arms mounted on the frame in insulated spaced relation thereto and to said contact plate, means electrically connecting one of said contact arms with the contact plate comprising a relay having the core and coil thereof supportably mounted on said contact plate with said core and one end of said coil electrically connected to said contact plate, means for connecting the other end of said coil to the other side of said source of potential for energizing said coil, and means including a pair of coacting switch elements rendered effective by the relay armature and electrically connected respectively with the relay core and with said one of the contact arms for electrically connecting the relay core with said contact arms.
40. In a contact stack for an electric motor of the magnetic type, a supporting frame, an electric circuit for said motor including a source of potential, a contact plate adapted to be connected with one side of said source of potential and mounted on said frame in insulated spaced relation thereto, a pair of contact arms mounted on the frame in insulated spaced relation thereto and to said contact plate, means electrically connecting one of said contact arms with the contact plate comprising a relay having the core and coil thereof supportably mounted on said contact plate with said core and one end of said coil electrically connected to said contact plate, means for connecting the other end of said coil to the other side of said source of potential for energizing said coil, and means including a pair of coacting switch elements rendered effective by the relay armature and electrically connected respectively with the relay core and with said one of the contact arms for electrically connecting the relay core with said contact arms.
45. In a contact stack for an electric motor of the magnetic type, a supporting frame, an electric circuit for said motor including a source of potential, a contact plate adapted to be connected with one side of said source of potential and mounted on said frame in insulated spaced relation thereto, a pair of contact arms mounted on the frame in insulated spaced relation thereto and to said contact plate, means electrically connecting one of said contact arms with the contact plate comprising a relay having the core and coil thereof supportably mounted on said contact plate with said core and one end of said coil electrically connected to said contact plate, means for connecting the other end of said coil to the other side of said source of potential for energizing said coil, and means including a pair of coacting switch elements rendered effective by the relay armature and electrically connected respectively with the relay core and with said one of the contact arms for electrically connecting the relay core with said contact arms.
50. In a contact stack for an electric motor of the magnetic type, a supporting frame, an electric circuit for said motor including a source of potential, a contact plate adapted to be connected with one side of said source of potential and mounted on said frame in insulated spaced relation thereto, a pair of contact arms mounted on the frame in insulated spaced relation thereto and to said contact plate, means electrically connecting one of said contact arms with the contact plate comprising a relay having the core and coil thereof supportably mounted on said contact plate with said core and one end of said coil electrically connected to said contact plate, means for connecting the other end of said coil to the other side of said source of potential for energizing said coil, and means including a pair of coacting switch elements rendered effective by the relay armature and electrically connected respectively with the relay core and with said one of the contact arms for electrically connecting the relay core with said contact arms.
55. In a contact stack for an electric motor of the magnetic type, a supporting frame, an electric circuit for said motor including a source of potential, a contact plate adapted to be connected with one side of said source of potential and mounted on said frame in insulated spaced relation thereto, a pair of contact arms mounted on the frame in insulated spaced relation thereto and to said contact plate, means electrically connecting one of said contact arms with the contact plate comprising a relay having the core and coil thereof supportably mounted on said contact plate with said core and one end of said coil electrically connected to said contact plate, means for connecting the other end of said coil to the other side of said source of potential for energizing said coil, and means including a pair of coacting switch elements rendered effective by the relay armature and electrically connected respectively with the relay core and with said one of the contact arms for electrically connecting the relay core with said contact arms.
60. In a contact stack for an electric motor of the magnetic type, a supporting frame, an electric circuit for said motor including a source of potential, a contact plate adapted to be connected with one side of said source of potential and mounted on said frame in insulated spaced relation thereto, a pair of contact arms mounted on the frame in insulated spaced relation thereto and to said contact plate, means electrically connecting one of said contact arms with the contact plate comprising a relay having the core and coil thereof supportably mounted on said contact plate with said core and one end of said coil electrically connected to said contact plate, means for connecting the other end of said coil to the other side of said source of potential for energizing said coil, and means including a pair of coacting switch elements rendered effective by the relay armature and electrically connected respectively with the relay core and with said one of the contact arms for electrically connecting the relay core with said contact arms.
65. In a contact stack for an electric motor of the magnetic type, a supporting frame, an electric circuit for said motor including a source of potential, a contact plate adapted to be connected with one side of said source of potential and mounted on said frame in insulated spaced relation thereto, a pair of contact arms mounted on the frame in insulated spaced relation thereto and to said contact plate, means electrically connecting one of said contact arms with the contact plate comprising a relay having the core and coil thereof supportably mounted on said contact plate with said core and one end of said coil electrically connected to said contact plate, means for connecting the other end of said coil to the other side of said source of potential for energizing said coil, and means including a pair of coacting switch elements rendered effective by the relay armature and electrically connected respectively with the relay core and with said one of the contact arms for electrically connecting the relay core with said contact arms.
70. In a contact stack for an electric motor of the magnetic type, a supporting frame, an electric circuit for said motor including a source of potential, a contact plate adapted to be connected with one side of said source of potential and mounted on said frame in insulated spaced relation thereto, a pair of contact arms mounted on the frame in insulated spaced relation thereto and to said contact plate, means electrically connecting one of said contact arms with the contact plate comprising a relay having the core and coil thereof supportably mounted on said contact plate with said core and one end of said coil electrically connected to said contact plate, means for connecting the other end of said coil to the other side of said source of potential for energizing said coil, and means including a pair of coacting switch elements rendered effective by the relay armature and electrically connected respectively with the relay core and with said one of the contact arms for electrically connecting the relay core with said contact arms.

THEODORE J. SCOFIELD.
